LIGHTING FIXTURES

Joseph Oster, Brooklyn, and Isidor Rosenblatt, New York, N. Y., assignors to Globe Lighting Products, Inc., Brooklyn, N. Y., a corporation of New York

Application January 15, 1953, Serial No. 331,406

13 Claims. (Cl. 240—78)

This invention relates generally to improvements in lighting fixtures and mounting means therefor, and, more particularly, to improvements in lighting fixtures of the type adapted to be mounted in a recess in the wall or ceiling of a room.

One of the important objects of the present invention is the provision of improved means for mounting a lighting fixture in a wall or ceiling recess. Pursuant to this object of the present invention the lighting fixture is provided with mounting means which may be retracted to permit the positioning of said fixture in a recess and after such positioning said mounting means may be moved to a securing position and secured in such position through the intermediation of devices accessible from the interior of said fixture whereby to provide for a simple, efficient, and attractive mounting arrangement.

Another object of the present invention is the provision of improved means for mounting a lighting fixture of the above character which is readily adapted for mounting said fixture in many different types of recessed installations.

Another object of the present invention is the provision of improved means for mounting a lighting fixture of the above character which does not interfere in any manner with the conventional mounting provision included in such fixture.

Another object of the present invention is the provision, in a lighting fixture, of reversible reflectors having its opposite faces formed with different light absorbing characteristics whereby said fixture is adapted to selectively reflect light corresponding to the face of the reflector which is disposed in light reflecting position.

Another object of the present invention is the provision of a lighting fixture having improved means for mounting its associated lens structure so as to define an unimpeded light passage around said lens structure.

Another object of the present invention is the provision of a lighting fixture having frame structure adapted for the detachable securement thereto of facing strips with the frame structure and facing strips being of dissimilar appearance whereby the appearance of the fixture may be selectively altered by detaching the facing strips from the frame structure.

Yet another object of the present invention is the provision of a generally improved lighting fixture which is relatively inexpensive to manufacture, simple to install, and which has a high degree of lighting efficiency.

The above and other objects, features and advantages of the present invention will be more fully understood from the following description considered in connection with the accompanying illustrative drawings.

In the drawings:

Fig. 1 is a plan view of a lighting fixture formed according to the present invention shown installed in a ceiling recess, viewing said fixture from a position below the ceiling with parts of said fixture being broken away to reveal structural details;

2

Fig. 2 is a view similar to Fig. 1 viewing said fixture from a position above the ceiling;

Fig. 3 is a sectional view taken on the line 3—3 of Fig. 2;

5 Fig. 4 is a sectional view taken on the line 4—4 of Fig. 2, on an enlarged scale;

Fig. 5 is a sectional view taken on the line 5—5 of Fig. 2, on a reduced scale;

10 Fig. 6 is a sectional view taken on the line 6—6 of Fig. 5;

Fig. 7 is a perspective view of a lens structure supporting bracket;

Fig. 8 is a perspective view of one of the fixture reflectors;

Fig. 9 is a fragmentary sectional view of the lighting fixture secured to supporting structure in a modified manner;

Fig. 10 is a view similar to Fig. 5 showing a modified form of installation;

20 Fig. 11 is a sectional view taken on the line 11—11 of Fig. 10; and

Fig. 12 is a fragmentary sectional view of a modified form of lighting fixture lens structure.

Referring to the drawings, and more particularly to

25 Figs. 1—4 thereof, the lighting fixture 10 formed according to the present invention is adapted for mounting in a wall or ceiling recess and comprises a housing 12 having lamp socket supporting means 14 secured therein. The housing 12 may be formed of any suitable material

30 and in the preferred embodiment is formed of sheet metal and comprises a pair of laterally spaced side walls 16 and 18, and a pair of laterally spaced end walls 20 and 22, said walls being preferably in integral relation. The housing 12 is further provided with a rear wall 24

35 which extends between the walls 16 and 18 and the walls 20 and 22 and is preferably in integral relation therewith. Thus the housing 12 is of quadrilateral formation although it is to be understood that said housing may have any desired configuration and may be formed

40 in any desired manner. Thus the peripherally extending walls 16 and 18, 20 and 22 define the outer periphery of said housing and the latter is adapted to be positioned in any suitable complementary dimensioned recess in a manner which will be described in detail hereinafter. Each of the walls 16, 18, 20 and 22 is provided

45 with an outwardly projecting longitudinally extending flange 26, the latter being adapted for the securement of the frame structure 28 to said housing. The housing frame structure 28, in the illustrated embodiment, is formed of wood and comprises four structurally identical

50 frame sections 30 which may be secured together in any desired manner and which are secured to the peripherally extending flanges 26 through the intermediation of any suitable fastener elements, for example screws 32. Each

55 of the sections 30 is a longitudinally extending member having inclined ends which are secured to adjacent complementary inclined ends of adjacent sections 30, as clearly shown in Figs. 1 and 2. The frame structure 28 is thus forwardly positioned relative to the housing 12, extending peripherally of said housing, and it will be

60 noted that said frame structure overhangs the peripherally extending walls 16, 18, 20 and 22 a substantial amount, as best shown in Figs. 3 and 4. The lamp socket supporting means 14 is conventional in all respects and is mounted in the housing 12 in a conventional manner.

65 More particularly, the socket supporting means 14 comprises a supporting shaft 34 which is mounted to the rear wall 24 of said housing, centrally thereof, by means of the spaced fastener elements 36. A suitable reflecting plate 38 is mounted in any desired manner to the rear wall 24 of housing 12 interiorly thereof and the fastener elements 36 which are threaded comple-

mentary to the shaft 34 are in abutting relation with the rear wall 24 and the reflector plate 38. The lamp socket supporting means 14 further comprises a bracket 40 which is supported by the shaft 34, said bracket having a plurality of lamp sockets 42 secured thereto with the latter being adapted for the reception of the bulbs 44 which constitute the light source of lighting fixture 10. It is to be understood that any suitable lamp socket supporting means 14 may be utilized and the specific means aforescribed is given by way of example only.

Pursuant to the present invention means are provided for securing the fixture housing 12 in the recess 46 formed in the ceiling C. The recess 46 in ceiling C is slightly larger than the housing 12 and is of a configuration complementary thereto, said housing being adapted to be supported by the ceiling C through the intermediation of the housing securing means which will now be described in detail. Each of the laterally spaced side walls 16 and 18 are provided with a pair of laterally spaced slots 48 which extend axially inwardly of the housing 12 to the rear wall 24 of said housing. The slots 48 at the rear wall 24 have a continuous portion 50 which extends laterally inwardly of said rear wall as best shown in Fig. 2, for a purpose which will be apparent from the description which follows. Each of the slots 48, having the continuous portion 50 extending laterally inwardly of the housing 12, are identically formed and companion pairs of such slots are adapted for association with a companion angle bracket 52, the latter comprising a mounting flange 54 and a projecting leg portion 56. The mounting flange 54 of each of the angle brackets 52 is provided with a pair of apertures 58 which are longitudinally spaced corresponding to the spacing of slots 48 on its associated side wall. Each of the angle brackets 52 is adapted for securement to its associated side wall by means of any suitable fastener elements which in the instant embodiment are screws 60. Thus each of the screws 60 extends through a companion slot 48 in the side walls and is received and extends through a companion aperture 58 for mounting the angle brackets 52 to the housing 12. It is to be noted that the screwheads of screws 60 are disposed so as to be accessible from within the housing 12, said disposition of the screwheads being adapted for a purpose which will subsequently be described. Thus the side walls 16 and 18 are each slotted in an identical manner and each has associated therewith a structurally identical angle bracket 52 which is adapted for the support of the fixture 10 in the recess 46.

Each of the brackets 52 is movable from a secured position which is shown in solid lines in Fig. 3 to a retracted position which is shown in said figure in broken lines, said brackets in said secured position being secured to its companion side wall by means of the fastener elements 60. In the secured position of the angle brackets 52, the projecting leg portions 56 of said brackets project laterally outwardly of their companion side walls so as to be in surface-to-surface relation with marginal edge portions 62 of the ceiling C defined by the recess 46 in said ceiling. Each of the angle brackets 52 is slidably movable to the retracted position indicated in broken lines in Fig. 3 by releasing or unscrewing screw 60 a sufficient amount whereby to permit the bracket to be slidably movable rearwardly and laterally of the housing 12 to said broken line position. By unscrewing screws 60 a sufficient amount the brackets 52 may be slidably moved rearwardly of the housing 12 and thereafter may be moved laterally inwardly of said housing whereby it will be apparent that the brackets 52 may be slidably moved to a retracted position in which the projecting leg portions 56 of said brackets lie inwardly of the plane of the side walls 16 and 18. Thus each of the brackets 52 is slidably movable axially inwardly of the housing 12 along the slots 48 and is movable laterally inwardly of said housing along the continuous slot portions 50 where-

by to provide for the retraction of each of the angle brackets 52 to a position lying within the projected area of the housing 12. In practice, the ceiling recess 46 is dimensioned complementary to the housing 12 so as to provide a small amount of clearance 64, and to permit the insertion of the housing 12 in said recess the angle brackets 52 are slidably moved to the retracted position shown in broken lines in Fig. 3. As best shown in Figs. 2-5 there is disposed upwardly of ceiling C in the region of recess 46 a pair of laterally spaced longitudinally extending joists or members 66 and the side walls 20 and 22 of the housing 12 are adapted to be positioned between such joists or members. Thus in the installation of Figs. 2-5 the members 66 are spaced apart a sufficient distance to permit the insertion therebetween of the housing 12 and, more particularly the side walls 20 and 22 thereof, and for securing said housing in the recess 46 the housing is moved axially inwardly of said recess so that the frame structure 28 is in abutting relation with the outer faces 70 of the marginal edge portions 62 defined by the recess 46. With the frame structure 28 so positioned the angle brackets 52 are slidably moved to the secured position shown in solid lines in Fig. 3, said slideable movement being possible by moving the fastener elements or screws 60 which are accessible from within the housing 12. Thus each of the angle brackets 52 is slidably moved laterally outwardly along the slot portions 50 and is thereafter moved axially outwardly of said housing until the projecting leg portions 56 of said brackets are in abutting relation with the inner faces 72 of the marginal edge portions 62 of the ceiling recess. With the angle brackets 52 so positioned the screws 60 are tightened so as to firmly secure the angle brackets 52 to a companion side wall of housing 12. It is to be understood that when the fixture 12 is mounted in a ceiling recess the brackets 52 will be gravitationally urged into abutting relation with the marginal edge portions 62 of the ceiling recess when said brackets are in the secured position. The securing of the angle brackets 52 in the secured position as aforescribed completes the mechanical installation of fixture 10 in the ceiling recess 46.

The side walls 20 and 22 of housing 12 are each further provided with a pair of elongated slots 74 which are adapted for the reception of fastener elements for mounting the fixture 10 in a modified manner. With reference to Fig. 9, there is shown a modified form of fixture installation in which the slots 74 are utilized, said slots being adapted for the reception of screws 76 for the securement of the housing 12 to the support members 78. The members 78, only one of which is illustrated, may be structurally similar to the joists or members 66 and in this modified form of installation the housing 12 is positioned in the recess 46 and is maintained in such position by means of the screws 76 which are received in the members 78, it being noted that each of said screws is screwed into an aperture 80 in member 78 from within the housing 12. Thus in the modified form of installation illustrated in Fig. 9, the angle brackets 52 are not utilized at all and do not interfere with this installation in any manner, said installation being effected by means of the screws 76 which extend through the side wall slots 74 and are received in apertures 80 of support members 78.

With reference to Figs. 10 and 11, there is shown a further modified form of fixture installation wherein the laterally spaced joists or members 82 are spaced apart a distance substantially greater than the distance corresponding to the length of the side walls 16 and 18. In this form of installation a pair of support members 84 are secured to the joists 82 in abutting relation with ceiling C and, more particularly, there is provided a pair of longitudinally extending support members 84 which are secured to the joists 82 in any desired manner and extend therebetween, said members 84 being in abutting relation with the marginal edge portion 62' of ceiling C defined

by the recess 46", which is formed similar to recesses 46 and 46' aforescribed. The members 84 are adapted to cooperate with the angle brackets 52 for the support of the fixture 10 in the ceiling recess 46", wherefore it will be apparent that said members 84 constitute supporting structure in said recess for the support of lighting fixture 10. In this form of installation the angle brackets 52 cooperate with members 84 in the same manner as aforescribed wherefore it will be apparent that such form of installation is identical with the installation illustrated in Figs. 1-4 except that the angle brackets 52 are in cooperative association with the members 84 instead of marginal edge portions of the ceiling proper as in the aforescribed installation. Accordingly the installation of Figs. 10 and 11 for fixture 10 is performed in a substantially identical manner as aforescribed with reference to Figs. 1-4 except that the brackets 52 are moved from a retracted position to a secured position in which the leg portions 56 of said brackets are in abutting relation with adjacent inner face portions of the members 84. Thus where the joists 82 are laterally spaced apart in a non-complementary fashion relative to the housing 12 it is merely necessary to affix said joists or members supporting structure, such as members 84, with the latter constituting the supporting structure adapted for cooperative association with the brackets 52 which are utilized for mounting the fixture in its associated wall or ceiling recess.

Secured to the rear wall 24 of housing 12 is a suitable channel member 86 which defines a passage 88 adapted for the reception therethrough of suitable conductors for electrically connecting the sockets 42 to a current source. The passage 88 of the channel member 86 communicates with the interior 91 of junction box 93, the latter being secured in any conventional manner to the side wall 18. It will be understood that suitable electrical conductors will extend from the sockets 42 to a source of current, said conductors extending through passage 88 into the interior 91 of the junction box 93. It will be understood that the junction box 93 may be positioned otherwise than as shown herein and that such junction box structure and the electrical connections between the socket 42 and a source of current is conventional in all respects.

Pursuant to another feature of the present invention, the lighting fixture 10 is provided with a plurality of reflectors 90 which are removably secured in housing 12 with either face thereof in light reflecting position. More particularly, each of the reflectors 90 is adapted for reversible mounting in the fixture 10 and comprises a flexible plate 92 having its opposite faces 94 and 96 formed with different light absorbing or reflecting characteristics. Thus the opposite faces 94 and 96 of plate 92 may be differently colored or may be coated differently whereby they may have different light absorbing or reflecting characteristics. Each of the plates 92 is formed of a flexible and resilient sheet metal material and is adapted to be concavely flexed as shown in Figs. 3 and 4 for the mounting thereof in lighting fixture 10. One side of plate 92 is provided with a cutaway portion 98 and the opposite side of said plate is notched as indicated at 100, said notch and said cutaway portion being adapted for purposes which will be apparent from the description which follows: In the illustrated embodiment the lighting fixture 10 is provided with four such reflectors 90 which are adapted to be mounted in the housing 12 in a position to reflect light from the bulbs 44. The reflectors 90, when secured in housing 12, form a continuous reflecting surface and if desired an opposite pair of said reflectors may be of greater longitudinal extent than the other opposite pair of reflectors whereby to provide for said continuous or uninterrupted reflecting surface. It will be apparent that during the mounting of the housing 12 in its associated recess the reflectors 90 will be detached from the housing wherefore to provide for accessibility to the fasteners 60. After the installation of housing 12 in its

associated recess is completed, the reflectors 90 will be mounted in position in housing 12 in a manner which will now be described. Each of the frame sections 30 of the frame structure 28 is provided with a longitudinally extending groove 102, said grooves being positioned adjacent to the plane of the walls which define the peripheral surface portion of the housing 12. The rear wall 24 of housing 12 is provided with tapped apertures 104 which are adapted for the reception of screws 106, said screws being adapted to register with the notches 100 of reflectors 90 for securing said reflectors in position in the housing. In practice, the edge 108 of each of the reflectors 90 will be positioned in the longitudinally extending slot 102 of a companion frame section 30 and will be concavely flexed until notch 100 registers with a companion aperture 104 of wall 24 and when such registry occurs screws 106 will be secured in said tapped apertures to complete the securement of the reflector 90 in the housing. Each of the reflectors 90 is secured in the housing 12 in a similar manner wherefore it will be apparent that a tapped aperture 104 will be provided for each of said reflectors, said apertures being positioned so as to provide for the concave flexure of the reflectors, as illustrated in Figs. 3 and 4. Reflectors 90 in their relaxed condition are of flat planar form and are adapted to be flexed in opposite directions whereby to provide for the reversibility of said reflectors. Thus the reflectors 90 may be readily reversed by detaching said reflectors from their associated mounting means and reversing such reflectors, it being noted that such reflectors are secured in housing 12 in the same manner regardless of which of their faces are positioned in housing 12 in position to reflect light outwardly of fixture 10. As previously noted each of the reversible reflectors 90 may have its faces formed with different light reflecting or absorbing characteristics whereby it will be apparent that a practically unlimited variety of different light reflecting combinations may be achieved. Thus the reflectors 90 are adapted to be mounted in the housing 12 with either face 94 and 96 thereof in light reflecting position whereby fixture 10 is adapted to selectively reflect light corresponding to the face of said reflector which is disposed in the housing in light reflecting position.

Fixture 10 is provided with lens structure 110 which is adapted for support relative to the housing 12 so as to define the substantially unimpeded light passage 112 between the periphery of said lens structure and the housing. The lens structure 110 comprises any suitable lens 114 which is framed and supported by the frame structure 116. The frame structure 116, which in the illustrated embodiment is formed of sheet metal, is peripherally continuous and is provided with a peripherally continuous flange 118 which is adapted to support the lens 114 at its marginal edges 115. The lens 114 is secured relative to its associated frame 116 by means of the angle brackets 124, each of said angle brackets having a projecting leg portion 126 which is adapted to be bent over adjacent marginal edge portions of the lens 114 for securing the latter in position. The lens structure 110 is conventional in all respects and may take any desired form, for example the form illustrated in Fig. 4 or the modified form illustrated in Fig. 12. The lens 114 as best shown in Fig. 4 is of flat planar formation whereas the lens 114 as illustrated in Fig. 12 is of generally dished shape. Furthermore lens 114 is of the prismatic type and from the above it is to be understood that the lenses 114 may be formed of any suitable material and may diffuse light in any desired manner, for example said lens may have any degree of transparency, or may be translucent or opaque. The lens structure 110 is adapted for support relative to housing 12 in the aforescribed manner through the intermediation of the lens supporting brackets 124 as shown in Fig. 7, it being noted that one of such brackets is adapted to be associated with each of the walls 16, 18,

20 and 22 of said housing for supporting the lens structure. Each of the brackets 124 comprises a flat metallic plate 126 having a bent-over portion 128 which is suitably apertured as indicated at 130 for the reception of fasteners for mounting the brackets to the housing 12. Each of the brackets 124 is adapted to be secured to an associated housing wall by means of screws 132 and said brackets are provided with a supporting finger 134 which is adapted to engage with adjacent portions of flange 118 of frame 116. The edge 136 of each of the brackets 124 is formed complementary to the frame structure 28 of the housing whereby to provide for a very neat and attractive installation for brackets 124. As noted above, each of the reflectors 90 is provided with a cutaway portion 98, said cutaway portion being adapted to provide the requisite degree of clearance for brackets 124 when the latter are secured to said housing. Thus the supporting fingers 134 of each of the brackets 124 extend laterally inwardly of the housing and marginal edge portions of the lens structure 110 are adapted to rest on the finger portions 134 and will be gravitationally urged into engaging relation with said fingers when said lens structure is supported by the brackets 124. Thus each of the brackets 124 is secured to the housing 12 in a position for supporting the lens structure 110 whereby an unimpeded light passage 112 is defined between the frame structure 28 and the light transmitting means, here constituted by the lens structure 110. Thus the light transmitting means 110 is dimensioned so that its outer marginal edges define an area substantially smaller than the area defined by the inner marginal edges of the frame structure 28 whereby the brackets 124 support said light transmitting means relative to the housing 12 to provide for the unimpeded light passage 112.

As aforementioned the frame structure 28 is formed of wood in the illustrated embodiment, although it is to be understood that said frame structure may be formed of any desired material and may be ornamented in any desired manner, for example the outer faces 29 of said frame structure may be provided with peripherally extending grooves 31 whereby to give to the fixture 10 an aesthetically desirable appearance. With reference to Fig. 4, the frame sections 30 have facing strips 140 positioned thereon, each of said facing strips being adapted for detachable securing to its companion frame section 30. Thus each of the facing strips 140 is formed complementary to a companion frame section 30 and means are provided to provide for the detachable securing of said strips to its companion frame section. Each of the facing strips 140 is provided with a longitudinally extending flange portion 142 which is adapted to mate with a complementary portion of its companion frame section, said flanges 142 having a longitudinally extending bent-in portion 144 which is adapted to snap engage with adjacent portions of its companion frame section. Thus the flange portions 142 having bent-in portions 144 are adapted to snap engage with the frame structure 28 to provide for the detachable securing of said facing strips to said frame structure. When the facing strips 140 are attached to the frame sections 30 the latter will be completely concealed from view whereby the appearance of the fixture may be selectively altered by detaching the facing strips from the frame structure. In practice, each of the facing strips 140 will be formed complementary to a companion frame section 30 and will completely conceal the latter when attached thereto. In the preferred embodiment said facing strips are formed of sheet metal presenting an aesthetically desirable appearance, it being noted that said facing strips may be formed of any suitable material and may have their outer faces ornamented in any desired manner. From the above it will be apparent that the outer face portions of the facing strips 140 and the outer face portions of the frame sections 30 are of dissimilar ap-

pearance whereby the appearance of the fixture may be selectively altered by detaching the facing strips from their companion frame sections 30. In Fig. 9 the frame section 30 is shown without a companion facing strip 140 positioned thereon whereas in Fig. 4 such frame section is shown having a facing strip 140 attached thereto.

In practice the housing 12 of the lighting fixture 10 aforementioned may be readily inserted in its complementary ceiling recess by tilting said housing a sufficient amount to permit the insertion of junction box 93 through said recess.

While we have shown and described the preferred embodiment of my invention, it will be understood that various changes may be made in the present invention without departing from the underlying idea or principles of the invention within the scope of the appended claims.

Having thus described our invention, what we claim and desire to secure by Letters Patent is:

1. A lighting fixture adapted for mounting in a wall or ceiling recess having fixture supporting structure, comprising a housing having a lamp socket supporting provision mounted therein, and means for securing said housing in said recess for support by said supporting structure, said means being movable from a retracted position in which said means lies within the projected area of a peripheral surface portion of said housing to a secured position in which said means overhangs said peripheral surface portion of said housing, said means cooperating with said supporting structure when the former is in said secured position for securing said housing in said recess.
2. A lighting fixture adapted for mounting in a wall or ceiling recess having fixture supporting structure, comprising a housing and means for securing said housing in said recess for support by said supporting structure, said means being movable from a secured position in which said means overhangs a peripheral surface portion of said housing for engagement with said supporting structure to a position in which said means is retracted inwardly of said secured position for facilitating the insertion of said housing in said recess.
3. A lighting fixture adapted for mounting in a wall or ceiling recess having fixture supporting structure, comprising a housing and means for securing said housing in said recess for support by said supporting structure, said means being movable from a secured position in which said means overhangs a peripheral surface portion of said housing for support by said supporting structure to a position in which said means is retracted inwardly of said secured position for facilitating the insertion of said housing in said recess, and means accessible from within said housing providing for the movability of said first mentioned means to said secured position.
4. A lighting fixture adapted for mounting in a ceiling recess having fixture supporting structure, comprising a housing having a lamp socket supporting provision mounted therein, means for securing said housing in said recess for support by said supporting structure, said means comprising a supporting bracket movably mounted on a peripherally extending wall portion of said housing, said wall portion being slotted, means for releasably fastening said bracket to said wall portion, said fastener means extending through said slot, the latter having a rear portion thereof extending laterally inwardly of a forward portion thereof whereby said bracket is movable from a secured position in which said bracket overhangs said wall portion for engagement with said supporting structure to a position in which said bracket is retracted laterally inwardly of said secured position for permitting the insertion of said housing in said recess.
5. A lighting fixture adapted for mounting in a ceiling recess having fixture supporting structure, comprising a housing having a lamp socket supporting provision mounted therein, said housing having a peripherally ex-

tending side wall and a rear wall, means for securing said housing in said recess for support by said supporting structure, said means comprising a supporting bracket movably mounted on said side and rear walls, the latter being provided with a continuous slot, means extending through said slot for releasably fastening said bracket to said side and rear walls, the portion of said slot in said rear wall extending laterally inwardly of the portion of said slot in said side wall whereby said bracket is movable from a secured position in which said bracket overhangs said side wall for support by said supporting structure to a position in which said bracket is retracted laterally inwardly of said secured position for permitting the insertion of said housing in said recess.

6. A lighting fixture adapted for mounting in a ceiling recess, comprising a housing having laterally spaced side walls and a rear wall extending therebetween, each of said side walls having slots extending axially of said housing to said rear wall, said slots at said rear wall extending laterally inwardly of the latter whereby each of said slots have a side wall portion and a continuous rear wall portion, angle brackets movably mounted on said housing, means extending through each of said slots for releasably fastening said angle brackets to said housing whereby each of said brackets is movable from a secured position in which said bracket is secured to said side wall and projects laterally outwardly thereof to a retracted position in which said bracket is slidably moved so as to lie inwardly of the plane of said side wall, said fastener means extending through said rear wall when said bracket is in said retracted position and extending through one of said side walls when said bracket is in said secured position.

7. A lighting fixture adapted for mounting in a ceiling recess, comprising a housing having laterally spaced side walls and a rear wall extending therebetween, said side walls and said rear wall being in integral relation, each of said side walls having at least a pair of laterally spaced slots extending axially inwardly of said housing to said rear wall, said slots at said rear wall having a continuous portion extending laterally inwardly of said rear wall, angle brackets movably mounted on said housing and adapted for slidable movement thereon along said slots, each of said angle brackets comprising a mounting flange and a projecting leg portion, means extending through each of said slots for releasably fastening each of said bracket mounting flanges to said housing side walls, each of said brackets being movable from a secured position in which said bracket is secured to a side wall by said fastening means and projects laterally outwardly of said side wall to a retracted position by the release of said fastening means in which said bracket is slidably movable rearwardly and laterally of said housing so that the leg portion thereof lies inwardly of the plane of said side wall.

8. A lighting fixture adapted for mounting in a ceiling recess, comprising a housing having laterally spaced side walls and a rear wall extending therebetween, said side walls and said rear wall being in integral relation, each of said side walls having at least a pair of laterally spaced slots extending axially inwardly of said housing to said rear wall, said slots at said rear wall having a continuous portion extending laterally inwardly of said rear wall, angle brackets movably mounted on said housing and adapted for slidable movement thereon along said slots, each of said angle brackets comprising a mounting flange and a projecting leg portion, means extending through each of said slots for releasably fastening each of said bracket mounting flanges to said housing side walls, each of said brackets being movable from a secured position in which said bracket is secured to a side wall by said fastening means and projects laterally outwardly of said side wall to a retracted position by the release of said fastening means in which said bracket is slidably movable rearwardly and laterally of said housing

ing so that the leg portion thereof lies inwardly of the plane of said side wall, said fastener means comprising screws accessible from within said housing.

9. A lighting fixture adapted for mounting in a ceiling recess, comprising a housing having laterally spaced side walls and a rear wall extending therebetween, said side walls and said rear wall being in integral relation, said housing having overhanging forwardly positioned frame structure extending peripherally of said housing, 5 each of said side walls having at least a pair of laterally spaced slots extending axially inwardly of said housing to said rear wall, said slots at said rear wall having a continuous portion extending laterally inwardly of said rear wall, angle brackets movably mounted on said 10 housing and adapted for slidable movement along said slots, each of said angle brackets comprising a mounting flange and a projecting leg portion, means extending through each of said slots for releasably fastening each of said bracket mounting flanges to said housing side walls, each of said brackets being movable from a secured position in which said bracket is secured to a side wall by said fastening means and projects laterally outwardly of said side wall so as to be in surface-to-surface relation with marginal edge portions of said ceiling 15 defined by said recess to a retracted position by the release of said fastening means in which said bracket is slidably movable rearwardly and laterally of said housing so that the leg portion thereof lies inwardly of the plane of said side wall whereby to permit the positioning 20 of said housing in said recess, said frame structure overhanging said ceiling marginal edge portions on the opposite side of said brackets in the installed condition of said fixture.

10. A lighting fixture adapted for mounting in a wall 35 or ceiling recess for support by marginal edge portions of said wall or ceiling which define said recess, comprising a fixture housing, and means for securing said housing in said recess for support by said marginal edge portions, said means being movable from a retracted position 40 in which said means is disposed within the projected area of a peripheral surface portion of said housing to permit the insertion of said housing in said recess, to a secured position in which said means projects laterally outwardly of said peripheral surface portion for engagement with 45 said marginal edge portions for support thereby.

11. A lighting fixture adapted for mounting in a wall or ceiling recess for support by marginal edge portions of said wall or ceiling which define said recess, comprising a fixture housing, and means for securing said housing 50 in said recess for support by said marginal edge portions, said means being movable from a retracted position in which said means is disposed within the projected area of a peripheral surface portion of said housing to permit the insertion of said housing in said recess, to a secured 55 position in which said means projects laterally outwardly of said peripheral surface portion for engagement with said marginal edge portions for support thereby, said housing having a forwardly disposed frame overhanging said housing and overhanging said marginal edge portions 60 forwardly thereof in the installed condition of said fixture.

12. A lighting fixture adapted for mounting in a wall or ceiling recess for support by marginal edge portions of said wall or ceiling which define said recess, comprising 65 a fixture housing, and means for securing said housing in said recess for support by said marginal edge portions, said means being movable from a retracted position in which said means is disposed within the projected area of a peripheral surface portion of said housing to 70 permit the insertion of said housing in said recess, to a secured position in which said means projects laterally outwardly of said peripheral surface portion for engagement with said marginal edge portions for support thereby, and means accessible from within said housing pro- 75

viding for the movement of said first mentioned means to said secured position.

13. A lighting fixture adapted for mounting in a wall or ceiling recess for support by marginal edge portions of said wall or ceiling which define said recess, comprising a fixture housing, and means for securing said housing in said recess for support by said marginal edge portions, said means being movable from a retracted position in which said means is disposed within the projected area of a peripheral surface portion of said housing to permit the insertion of said housing in said recess, to a secured position in which said means projects laterally outwardly of said peripheral surface portion for engagement with said marginal edge portions for support thereby, reflector means removably secured in said housing in position to

15

reflect light, said reflector means having its opposite faces formed with different light reflecting characteristics, said reflector means being mountable in said housing with either face thereof in light reflecting position whereby said fixture is adapted to selectively reflect light corresponding to the face of said reflector means which is disposed in said housing in light reflecting position.
